CLAIM

The ornamental design for an air cooled refrigeration
condenser, substantially as shown and described.

DESCRIPTION

FIG. 1 is a top perspective view of an air cooled refrigeration condenser showing our new design in its first embodiment, with the rear being plain and unornamented;

FIG. 2 is a left side elevational view of a second embodiment thereof;

FIG. 3 is a right side elevational view thereof; and

FIG. 4 is a top plan view thereof.

FIG. 1

FIG. 2

FIG. 3
